UNITED STATES PATENT OFFICE.

WAYNE W. BLACKBURN, OF ST. PETERSBURG, FLORIDA.

PUMP.

1,282,734.

Specification of Letters Patent. Patented Oct. 29, 1918.

Application filed July 28, 1915. Serial No. 42,390.

To all whom it may concern:

Be it known that I, WAYNE W. BLACKBURN, a citizen of the United States, residing at St. Petersburg, in the county of Pinellas and State of Florida, have invented 5 certain new and useful Improvements in Pumps, of which the following is a specification.

My invention relates to pumps and more 10 particularly to that type wherein a turbine is employed preferably for dredging purposes.

The primary object of my invention resides 15 in the provision of an improved means associated with the blades of the fan or turbine for causing the liquid that is being pumped to pass directly through the fan during the operation thereof thus increasing the efficiency of the pump, said means also 20 serving another purpose, that of preventing the throwing of the water laterally from the blades as well as incidentally serving the purpose of increasing the efficiency of the joint between the sections of the pump 25 cylinder.

A further object of my invention resides 30 in the provision of a device of the character described that is simple in construction, efficient in operation and one that can be manufactured and placed on the market at a minimum cost.

Other objects as well as the nature, characteristic features and scope of my invention will be more readily understood from 35 the following description taken in connection with the accompanying drawings and pointed out in the claim forming a part of this specification.

In the drawing:—

Fig. 1 is a side elevational view of my 40 invention;

Fig. 2 is a longitudinal central sectional view of the pump cylinder showing the fan positioned therein; and

Fig. 3 is a transverse sectional view taken 45 on the line 3—3 of Fig. 2 in the direction in which the arrow points.

Referring more particularly to the drawings in which similar reference numerals 50 designate like or corresponding parts throughout the different views, I provide a pump cylinder formed preferably of two conical shaped sections 1 and 2, said sections having flanges 3 projecting from their enlarged ends for facilitating the connection of the sections through the medium of fasten-

ing devices preferably bolts 3 which extend through the flanges and have their terminals engaged by nuts 4. An inlet pipe 5 has connection with the cylinder at one apex, connection between the apex of the cylinder and inlet being facilitated through the medium of a collar 6. The inlet is controlled through the medium of a check valve 7 associated therewith. The section 2 60 is provided with an opening 8 having a collar 9 formed thereabout, the latter receiving an outlet pipe 10, preferably in screw-threaded engagement with the coil.

In order to support the inlet and consequently the pump cylinder, I have provided standards 11 and 12, the standard 11 having an opening therethrough for supporting a portion of the inlet 5 as illustrated to advantage in the drawing. The opposite end 70 of the cylinder or section 2 has its apex rigidly supported in the combination bearing and stuffing box. This arrangement is provided in the upper end of the standard 12 and includes preferably an inwardly extending recess 13 having packing material 14 therein, the bottom of the recess having an opening 15 formed therein.

In order to create a vacuum within the cylinder and consequently draw liquids 85 thereinto through the inlet and force them through the outlet, preparatory to the securing of the sections 1 and 2 of the cylinder together, I have rotatably mounted in the opening 15 and in the apex of the section 2, 90 a shaft 16, the inner end of which terminates approximately in a plane in alinement with the joint formed at the base of the sections 1 and 2, and which shaft has rigidly mounted thereon my improved fan or turbine 17. In this instance the fan includes a collar having a plurality of blades 18 projecting radially therefrom, the terminals of the blades having secured thereto a ring or shroud 19, formed preferably of brass, 100 through the medium of suitable securing elements 20. This ring incidentally forms the essential part of this invention and is arranged in close relation with the point of juncture of the sections 1 and 2. By this 105 arrangement it is readily apparent that the water or other liquid being drawn through the cylinder will be consequently forced to pass through the propeller itself, thus increasing the efficiency of the operation of 110 the arrangement. It will also be noted that the water will not be thrown against the

point of juncture of the sections and as a result the efficiency of the joint will not be affected.

In order to rotate the fan and consequently create a suction within the cylinder which naturally draws liquid into the inlet and forces it through the outlet, I have mounted a gear 21 on the free projecting end thereof, said gear being in mesh with a smaller gear 22 carried on the rotating shaft 23 of a motor 24, the latter constituting a suitable source of power.

Although I have shown and described the preferred embodiment of my invention I desire to be understood that I am not to be limited to the exact details shown, however, I desire that great stress be laid upon the arrangement of the means as associated with the fan for performing the dual purpose of increasing the efficiency of the fan as well as providing a means for protecting the joint between the two sections of the cylinder. These sections as is obvious can be detached when it is desired to clean the cylinder on the interior thereof. When starting the pump it is first necessary to fill the same with water so that when the fan is rotated it will cause a suction through the inlet, which suction will incidentally draw the water into the cylinder through the inlet and discharge it through the outlet.

From the above description taken in connection with the accompanying drawings, it can easily be seen that I have provided a device that is simple in construction, containing but a few simple parts that can be cheaply manufactured and assembled and when assembled can be placed upon the market and sold at a minimum cost.

It will be understood that the above de-

scription and accompanying drawings comprehend only the preferred embodiment of my invention and that various minor changes in detail of construction, proportion and arrangement of the parts may be made within the scope of the appended claim and without sacrificing any of the advantages of my invention.

Having thus fully described my invention, what I claim as new and desire to secure by Letters Patent, is:—

A pump comprising in combination with spaced standards having openings therein, a cylinder composed of two separable conical sections, each section being provided on its largest diameter with a flange extending outwardly therefrom and the smaller ends terminating in cylindrical extensions adapted to be received in the openings in the standards, means passing through the flanges for securing the sections together, said cylinder being formed interiorly with a bearing surface at the juncture of the two sections, a rotatable shaft passing through the cylindrical extension on one section and projecting into the cylinder, an impeller mounted upon the inner end of the shaft, said impeller being provided circumferentially with a shroud adapted to rotate in the bearing surface formed at the juncture of the sections and thus serve to support the shaft at the impeller end, means for rotating the shaft and therefrom the impeller, and inlet and out ports.

In testimony whereof I affix my signature in presence of two witnesses.

WAYNE W. BLACKBURN.
